CARBURETOR

Augustin M. Prentiss, San Antonio, Tex., assignor
to Bendix Aviation Corporation, South Bend,
Ind., a corporation of Delaware

Application February 1, 1932, Serial No. 590,293

17 Claims. (Cl. 261—34)

This invention pertains to carburetors and more particularly has reference to temperature controlled acceleration devices for carburetors of the pressure feed type.

5 This invention is an improvement on the invention disclosed in my United States Patent 1,329,309, issued January 27, 1920, and this application is a continuance in part of my copending application Serial No. 520,292, filed February 1, 1932.

10 In the pressure feed type of carburetor shown in my copending application, Serial No. 580,992, filed December 14, 1931, and Serial No. 590,292, no special apparatus was provided for acceleration, sole reliance being placed on the greatly superior 15 performance secured by the use of a compressed air liquid fuel feed. I have found that, while the acceleration performance of the pressure feed carburetor greatly excels that of the conventional vacuum feed carburetor, there is a need for 20 temperature control of the acceleration fuel supply. I have also found that even more rapid acceleration at lower temperatures can be secured through a momentary augmentation of the acceleration fuel supply even in pressure feed carburetors.

25 An object of this invention is to provide a carburetor of the pressure-feed type wherein the normal liquid fuel supply is temporarily augmented when the throttle is opened so as to still further increase the acceleration of the engine.

30 Another object of this invention is to provide a carburetor of the pressure-feed type wherein the supply of additional liquid fuel for acceleration is regulated in accordance with the temperature of the carburetor so that, as this temperature increases the acceleration fuel supply decreases.

35 Still another object of this invention is to provide a carburetor of the pressure-feed type wherein the acceleration device is combined with the device for regulating the additional compressed 40 air supply required for compensation of the mixture delivered by the main jet.

45 With these and other objects in view which may be incident to my improvements, my invention consists of the combination and arrangement of elements hereinafter described and illustrated in the accompanying drawing which Figure 1 shows, in central vertical section a carburetor embodying my improvements.

50 Figures 2 and 3 are fragmentary longitudinal sections of the acceleration pump looking in the directions of arrows 2 and 3 respectively.

55 Referring to the drawing, the reference numeral 1 denotes the body of a carburetor having a main air intake 2, Venturi throat 3, mixing chamber 4,

and mixture outlet 5 controlled by a butterfly throttle valve 6. The term "mixing chamber" as used in this application does not include the portion of the passage which lies posterior to the throttle. Integral with the bottom wall of air intake passage 2, is a main jet nozzle 7 which rises to a point just above the center of throat 3 and consists of an outer liquid fuel tube 8 and a concentric inner compressed air tube 9. Tube 8 is surmounted by an adjustable screw-threaded cap 10 having a central aperture 11 through which the compressed air and liquid fuel issue in the form of a finely atomized spray. It will be appreciated that the relative positions of the air and liquid fuel tubes may be reversed without appreciably affecting the functioning of nozzle 7 or departing from the spirit of my invention. Liquid fuel tube 8 communicates through a passageway 12 and port 13 with a liquid fuel reservoir 14 into which liquid fuel under superatmospheric pressure enters through an inlet 15 controlled by a valve 16 which is actuated by a float 17 to maintain the liquid fuel at a normal level X—X in the usual manner. The normal flow of liquid fuel from reservoir 14 to nozzle 7 is controlled by a manually adjusted valve 18 which regulates the free opening through port 13.

60 Air tube 9 communicates through an air passageway 19 and metering restriction 19a with a second air passage 20 which in turn communicates through a compressed air supply pipe 21 with a constant pressure air pump (not shown).

65 A constant superatmospheric air pressure is maintained in reservoir 14 during the operation of the carburetor by means of a metering restriction 22, which admits compressed air into reservoir 14 from air passage 20, and a second smaller metering restriction 23 which permits compressed air to escape from reservoir 14 into the atmosphere at such a controlled rate as will maintain the desired pressure in reservoir 14.

70 Integrally attached to the bottom wall of reservoir 14 is a cylinder 24 which is divided by a transverse wall 25 into an upper chamber 26 and a lower chamber 27. Chamber 26 communicates through a pipe line 28, passageway 29 and port 30 with mixing chamber 4 and through a series of ports 31 with reservoir 14. Adapted to reciprocate within chamber 26, with an air-tight fit, is a piston 32 having adjustably attached thereto a piston rod 33 which passes through a liquid-tight stuffing box 34 in wall 25 and is similarly attached by screw threads to a second piston 35 adapted to reciprocate in chamber 27 also with an air-tight fit. Interposed between

piston 32 and the top of chamber 26 is a helical spring 36 which is arranged to force piston 32 down in opposition to the action of the vacuum in mixing chamber 4 which is transmitted to chamber 26 through passage 29 and pipe 28.

Integrally attached to piston 35 is a sleeve valve 37 which is adapted to slide in a valve chamber 38 integrally attached to the bottom wall of reservoir 14 and depending therefrom, as clearly shown in the drawing.

Valve chamber 38 communicates with air passage 20 through a generally triangular shaped port 39 which admits compressed air into chamber 38 whenever valve 37 is raised and uncovers a part of said port. The shape of port 39 is not truly triangular but the sides thereof are curved so that the area uncovered by valve 37 at any given position is sufficient to pass the exact quantity of air required to form a mixture of desired proportions, under the degree of vacuum existing in mixing chamber 4 at the time, as explained in my copending application, Serial No. 590,292 above referred to. Chamber 38 communicates with mixing chamber 4 by means of connecting passageways 40, 41, 42 and 43 and a slot-shaped port 44 in sleeve valve 37, the width of which port is equal to the diameter of passageway 40 which is also equal to that of passageway 20.

Chamber 27 communicates with liquid fuel tube 8 by means of a pipe line 45 and with reservoir 14 by means of exhaust port 46 and intake port 47, the former being normally closed by a spring pressed check valve 48 which is adjusted by a screw 49 threaded through a three-legged yoke 50 attached by screws 51 to the outside wall of cylinder 24. The legs of yoke 50 function as a guide for the ball 48. Port 47 is so positioned as to be normally closed by sleeve valve 37 and opened only when this valve is in its lowermost position. A small notch 52 is cut in the top edge of piston 35 which is arranged to register with port 46 when piston 35 is in its uppermost position and with port 47 when piston 35 is in its lowermost position, as clearly shown in the drawing.

Communication between chamber 27 and tube 8 through pipe line 45 is regulated by a valve 53 which is actuated by a thermostatic element 54 attached to pipe 45 and so calibrated as to raise valve 53 by a predetermined amount for each degree fall in temperature of the carburetor. Valve 53 is adjustably connected to thermostat 54 by a plurality of nuts which are threaded on valve stem 53 and embrace element 54.

With the arrangement just described it is apparent that valve 53 is fully open only at the lowest working temperature of the carburetor and as this temperature rises valve 53 gradually restricts passageway 45 so that it is completely closed at the highest operating temperature of the carburetor. In this way the additional liquid fuel supplied for acceleration through pipe 45 is regulated in accordance with the temperature of the carburetor.

The operation of my device is as follows: When the engine is idling at its slowest speed the throttle is in its most restricted position, as shown in the drawing. In this position the clearance between the walls of the mixture outlet 5 and the throttle 6 is just sufficient to pass the amount of mixture required for idling. Under these circumstances the vacuum in mixing chamber 3 and chamber 26 is at a minimum, and spring 36 forces pistons 32 and 35 and sleeve valve 37 to their

lowest positions, thus cutting off the auxiliary compressed air supply through passages 40, 41, 42, and 43 from passage 20. When piston 35 is in its lowest position, port 47 is opened and liquid fuel enters chamber 27 from reservoir 14, also all liquid fuel is expelled from chamber 26 through ports 31 into reservoir 14.

As throttle 5 is opened there is an increase in vacuum in mixing chamber 4 and chamber 36 which draws pistons 32 and 35 and valve 37 up in proportion as this vacuum increases. As piston 35 ascends it compresses the liquid fuel in chamber 27 and forces it out through exhaust port 46 and pipe 45. The volume of liquid thus escaping from chamber 27 through these exits is inversely proportional to the resistances encountered in each, and as port 46 is a relatively larger, shorter and more direct passage than pipe 45, its hydraulic resistance is very much less and a far greater volume of liquid normally escapes through port 46 as compared to pipe 45. The tension in the spring holding ball check valve 48 to its seat may be so adjusted by screw 49 as to make the resistance offered by the ball to the escape to liquid from chamber 27 negligible. In this case, the function of ball 50 is merely to prevent liquid fuel from entering chamber 27 through port 46.

The area of port 46 is made such that, when piston 35 is raised slowly, this port is sufficient to discharge liquid fuel from chamber 27 without developing enough pressure to cause an appreciable discharge of liquid fuel through pipe 45, even when valve 53 is open. However, when piston 35 is raised quickly, the area of port 46 is not sufficient to discharge the liquid fuel in chamber 27 without developing a pressure which causes a vigorous discharge of liquid fuel through pipe 45 and nozzle 7 into mixing chamber 4, whenever valve 53 is opened. When valve 53 is closed the time of evacuation of chamber 27 is slightly increased due to the reduction in the total area of discharge ports. This correspondingly slows up the travel of piston 35 on its upward stroke and also the rate of opening of valve 39. This last prevents too sudden an increase in the air component during acceleration which is desirable when no acceleration fuel is supplied (valve 53 closed). But valve 53 is only closed when the engine is at its highest working temperature, at which time acceleration is least difficult, provided the mixture is not impoverished by a sudden increase in the air component which is here prevented as just indicated above.

From the foregoing it is apparent that the stroke of piston 35 is regulated in accordance with the vacuum at port 30, so that as the vacuum increases the stroke of piston 35 increases and the amount of acceleration fuel supplied to the mixing chamber likewise increases in direct proportion.

It is also apparent that since valve 37 and piston 35 move as a unit, as long as valve 53 is open, the supply of acceleration fuel to the mixing chamber is accompanied by a corresponding and proportionate supply of compressed air through air lines 20, 40, 41, 42 and 43.

Ports 31 in the walls of chamber 26 permit a free flow of liquid fuel into and out of chamber 26 whenever piston 32 reciprocates therein so that no resistance or retardation is offered to the movement of piston 32 except to steady it against vibrations due to minor fluctuations of vacuum in mixing chamber 4.

As the throttle is closed, the vacuum in mixing chamber 4 decreases and spring 36 returns pistons 32 and 35 and valve 37 to the bottom of their

125

130

135

strokes, thus cutting off the compressed air supply through passages 20, 40, 41, 42 and 43 and permitting chamber 27 to refill with liquid fuel which enters from reservoir 14 through port 47 and from nozzle 6 through pipe 45 if valve 53 is open. The acceleration device is now ready for another cycle of operation.

Since valve 53 varies the opening in pipe 45 in accordance with the carburetor temperature it is obvious that the amount of acceleration fuel supplied to the mixing chamber is also regulated in accordance with temperature so that as the temperature rises the amount of acceleration fuel supplied diminishes, as required for best operating results.

If desired, the spring holding check valve 48 to its seat may be made of thermally sensitive metal so as to vary the resistance of the spring with change in temperature. By making the 20 spring increase in strength with fall in temperature, a greater feed of acceleration fuel can be forced out through pipe 45 at each stroke of piston 35 and also the duration of the acceleration fuel supply can be thus prolonged as the temperature falls. Also, if it is desired to increase the 25 sensitiveness of the acceleration device and prolong its output, a weighted flap valve 55 can be hung in air intake passage 2 as shown on the drawing. When this is done, passage 2 is made 30 square instead of circular in cross section so that valve 55 will lie flat against the top wall of passage 2 when fully open, so as not to restrict the opening through passage 2.

The force of gravity acting on valve 55 tends 35 to keep it in a vertical (closed) position and the air drawn through passage 2 into mixing chamber 4 tends to swing the valve from its vertical position in accordance with the velocity of the air stream passing through passage 2, so that valve 55 assumes a horizontal position when the air passing through passage 2 reaches its maximum velocity. But since valve 55 has an appreciable mass and inertia, it requires an appreciable time to move from its closed to open position, and during that interval of time, the vacuum 40 in mixing chamber 4, due to the opening of throttle 5, is more slowly reduced by the retardation of the air stream through passage 2 due to the inertia of valve 55. The effect of valve 55 is 45 therefore to temporarily increase and retard the decrease of vacuum in mixing chamber 4, whenever throttle 5 is opened and this in turn increases the force and duration of the acceleration discharge.

50 From the foregoing disclosure it will be appreciated that I have not only produced a novel temperature controlled acceleration device for pressure feed carburetors, but have so combined this device with the auxiliary air valve as to co-ordinate its action therewith, and reduce the total mechanism required for these functions to a minimum.

While I have shown and described the preferred embodiment of my invention, I desire it 55 to be understood that I do not limit myself to the precise details of construction shown by way of illustration, as these may be changed and modified in combination and arrangement by those skilled in the art without departing from the spirit of my invention or exceeding the scope 60 of the appended claims.

I claim:

1. In a carburetor having a throttle, a mixing chamber, means for supplying said chamber with liquid fuel under a continuous superatmospheric

pressure, and an acceleration device subjected to said pressure and responsive to the vacuum in said chamber for temporarily increasing said liquid fuel supply when said throttle is opened.

2. In a carburetor having a throttle, a mixing chamber, and means for feeding into said chamber liquid fuel under a continuous superatmospheric pressure and means responsive to the vacuum in said chamber for temporarily increasing said pressure when said throttle is opened, whereby said liquid fuel feed is temporarily increased at the same time.

3. In a carburetor having a throttle, a mixing chamber, means including a constant level fuel reservoir for supplying said chamber with liquid fuel under a continuous superatmospheric pressure, and temperature-regulated means within said reservoir for temporarily increasing said liquid fuel supply when said throttle is opened.

4. In a carburetor having a throttle, a mixing chamber, and means for feeding into said chamber liquid fuel under a continuous superatmospheric pressure, and vacuum controlled means for temporarily increasing said pressure when said throttle is opened, whereby said liquid fuel feed is temporarily increased at the same time, and a temperature responsive fuel valve for regulating said temporary increase of fuel feed in accordance with the temperature of the carburetor.

5. In a carburetor having a throttle, a mixing chamber, means for supplying said chamber with liquid fuel and air, both under continuous superatmospheric pressures, and unitary automatic means for temporarily increasing said liquid fuel supply and increasing said air supply when said throttle is opened.

6. In a carburetor having a throttle, a mixing chamber, means for supplying said chamber with liquid fuel and air, both under continuous superatmospheric pressures, and unitary vacuum-actuated means for temporarily increasing said liquid fuel supply and increasing said air supply when said throttle is opened.

7. In a carburetor having a throttle, a mixing chamber, and means for feeding into said chamber liquid fuel and air, both under continuous superatmospheric pressures, and unitary automatic means for temporarily increasing said liquid fuel pressure and increasing said air supply when said throttle is opened.

8. In a carburetor having a throttle, a mixing chamber, an atmospheric air supply to said chamber, means for feeding compressed air to supply to said chamber liquid fuel under a continuous superatmospheric pressure, and automatic means for temporarily retarding said air supply and increasing the pressure on said liquid fuel when said throttle is opened, whereby said liquid fuel feed is temporarily increased at the same time.

9. In a carburetor having a throttle, a mixing chamber, means for supplying said chamber with atmospheric air and with liquid fuel under a continuous superatmospheric pressure, and means for temporarily retarding said air supply and increasing said liquid fuel supply when said throttle is opened.

10. In a carburetor having a throttle, a mixing chamber, means for supplying said chamber with liquid fuel and air, both under different continuous superatmospheric pressures, and unitary automatic means for temporarily increasing said liquid fuel supply and increasing said air supply when said throttle is opened.

11. In a carburetor having a throttle, a mixing

- chamber, means for supplying said chamber with liquid fuel and air, both under different continuous superatmospheric pressures, and vacuum-actuated means for temporarily increasing said liquid fuel supply and increasing said air supply when said throttle is opened. 6
12. In a carburetor having a throttle, a mixing chamber, means for supplying said chamber with liquid fuel under a continuous superatmospheric pressure, and vacuum-actuated temperature-regulated means for temporarily increasing said liquid fuel supply when said throttle is opened. 10
13. In a carburetor having a throttle, a mixing chamber, and means for feeding into said chamber liquid fuel and air both under continuous superatmospheric pressures and unitary automatic means for increasing said air feed and temporarily increasing said liquid fuel feed when said throttle is opened. 15
14. In a carburetor having a throttle, a mixing chamber, and means for feeding into said chamber liquid fuel under a continuous superatmospheric pressure and vacuum-controlled means for temporarily increasing said pressure when said throttle is opened, whereby said liquid fuel feed is temporarily increased at the same time, and means for regulating said temporary increase 20
- 25
- of fuel feed in accordance with the temperature of the carburetor. 80
15. In a carburetor having a throttle, a mixing chamber, means for supplying said chamber with liquid fuel and air under continuous superatmospheric pressures, and vacuum-controlled means for temporarily increasing said liquid fuel supply when said throttle is opened, and means for regulating said temporary increase of fuel supply in accordance with the temperature of the carburetor. 85
16. In a carburetor having a throttle, a mixing chamber, means for supplying said chamber with liquid fuel and air under a continuous superatmospheric pressure, and an acceleration device, subjected to said pressure, for temporarily increasing said liquid fuel supply when said throttle is opened. 90
17. In a carburetor having a throttle, a mixing chamber, and means for feeding into said chamber liquid fuel and air under a continuous superatmospheric pressure, and an acceleration device, subjected to said pressure, for temporarily increasing said pressure when said throttle is opened, whereby said liquid fuel and air feeds are 100 temporarily increased at the same time. 95
